UNITED STATES PATENT OFFICE.

DOLPHUS TORREY, OF NEW YORK, N. Y.

CAR-BRAKE.

SPECIFICATION forming part of Letters Patent No. 276,981, dated May 1, 1883.

Application filed June 17, 1882. (No model.)

To all whom it may concern:

Be it known that I, DOLPHUS TORREY, a citizen of the United States, residing in the city, county, and State of New York, have invented 5 certain new and useful Improvements in Draw-Bar Brakes, of which the following is a specification.

The primary object of this invention is to effect an application of the brakes by either 10 the compression or extension of the draw-bar of the car to which it is attached, and to automatically control the engaging devices, so that the brakes will be applied by the appropriate movement of the draw-bar, this alternate adjustment being effected by changes in the direction of wheel rotation and by the use of balanced brake-beams.

The invention further relates to appliances by which the stress of the draw-bar, as the 20 braking movement of the draw-bar progresses, is applied to the brakes with greater force and with smaller relative motion.

The invention further relates to devices for effecting a tentative application of the brakes, 25 so that the apparatus will be automatically adjusted to correspond with the position of the car relatively to the engine, in order to effect the application of the brakes by a reversed movement of the draw-bar, either of extension 30 or compression.

The invention further relates to a device by which the intensity of force applied to the 35 brakes is limited by a spring of variable pressure, and relatively to the load and weight of the car.

The invention further consists in details by which the several objects above referred to are carried into effect, as hereinafter explained.

In the accompanying drawings, Figure 1 is 40 a vertical longitudinal section of a car-truck with the lower portion of the body-frame and brake attachments, illustrating the invention. Fig. 2 is a plan of the same. Fig. 3 is a transverse section on the line 3 3, Figs. 1 and 2. 45 Fig. 4 is a detail under side view of the draw-bar pitman, motor-lever, counter-balance support for the latter, and a slotted guide-plate for producing differential leverage. Fig. 4^a is a vertical section on the line 4^a 4^a of Fig. 4. 50 Fig. 5 is a side elevation and plan of the chain-loop carrier. Fig. 6 is a plan and side elevation of the motor-lever. Fig. 7 is an elevation

of a modified device for operating the engagement-bar to connect or disconnect the motor-lever and chain-loop carrier.

55

In Fig. 1 the fulcrum of the system of rods and levers of the hand-brake is the pulley b³ on the frame of the car, there being a loop of chain from the brake-lever f' to the pulley b³ over the pulley b². The brake mechanism is 60 connected with one line of the chain at a. The manner of making this connection is shown in Fig. 2. A pitman, y, is pivoted by a bolt to the draw-head at c, and lies parallel with it, extending to d, where it is bolted to a lever 65 lying transversely to the car. This lever x is pivoted at e to a draft-timber, and has a connection, through the chain-carrier g, with the chain f b b', said chain being connected to the carrier g at a a, as shown in Fig. 5. Any movement of the draw-bar, either out or in, swings the lever x in a corresponding direction, and it moves the connected chain-carrier with it, thus applying the brakes, except when this effect is prevented by the adjustment of the 70 mechanism, as hereinafter described. The chain f b b' is attached at a to the block or carrier g, sliding upon guides in line parallel with the chain. Upon the top of this block is a projecting lug, h, of the same height as the 75 thickness of the lever x.

Parallel with the guide-rods i, on which the chain-block slides, and above it, is a flat bar of iron, j, Fig. 1, turning on journals at its ends. The position of rest of this bar, which is called 80 the "disengagement-bar," is with its edge down, in which position it lies quite close to the top of the lug h on the chain-block g. This disengagement-bar is so connected with the brake-beams that as they shift their positions, 85 in consequence of changes in the direction of wheel rotation, they cause it to rotate half a revolution. By this rotation it, in turning its side toward the lug, leaves vacant a space between itself and the lug g, and thus permits 90 the passage of the lever x over the top of the lug h. It will be seen that any movement of the draw-bar which moves the lever x against the lug of the chain-carrier will tend to put 95 on the brakes, if the beams are set for the existing direction of wheel rotation, while if the beams are not so set their application will cause the beams to shift their position, in doing 100 which the disengagement-bar is rotated,

giving a chance for the lever x to pass over the lug h and avoid an application of the brakes. Such a slope is given to the bearing-surface of the lug and the lever as to cause this action to occur.

The brake-beams are so connected as to be in the condition known as "balanced"—that is, one rises and the other falls a short distance in the direction of the rotation of their respective wheels, as is more fully described in my application for a patent filed the 16th day of December, 1881. The chain-carrier moves in a line tangent to the arc swept by the lever x . To insure a definite point of contact in all parts of the arc between the lever and the lug, and to provide at the same time the required slopes a little in excess of the angle of friction, so that the lever will, when pressed in contact with the lug, be able to slide over it, the lug has the form of the frustum of a cone. The end of the arm or lever x , if made with plane surfaces at its edges, will, as it sweeps through its arc, tend to pull the chain-carrier g laterally with whatever degree of stress is due to the coefficient of friction made by their contact. This possible disturbance of the desired action from their contact is avoided by giving the edge of the lever a curved outline so determined as to make the contact-surfaces meet radially at the angle of friction. This gives a form to the end of the lever something like that shown in Figs. 4 and 6. Further, the edge has to be beveled to correspond to the slope of the lug of the chain-carrier.

As the direction of wheel rotation has two conditions of related movements to the movements of the draw-bar, depending upon the position of the engine relatively to the car, it will occur, when trains are made up, that it is necessary to shift the position of the balanced brake-beams without change of adjustment between the lever x and the chain-carrier. This is accomplished automatically by means of what is called a "tentative engagement," which is a slight engagement, only sufficient to cause the brake-beams to shift their position, and is effected by the swing of the lever x in its free direction. The devices for accomplishing this tentative engagement include the addition to the lever x of an arm, x' , extending across the lower face of the chain-carrier at such a distance from the principal arm x of said lever as to permit it to pass freely over the top of its lug. Further, two lugs, k , are placed on the lower face of the chain-carrier g at points equidistant from its center, as shown in Fig. 5, for the purpose of affording points of contact for the arm x' with the carrier as the former moves the block in a reverse direction to that given it by the arm x , acting on the lug h . The lever x is sustained, when idle, in a horizontal plane, as shown in section in Fig. 5, at the summit of the base-slopes on one side of the lug h . This horizon of movement is maintained by means of the bar l , on which the lever x slides at or near the

center of its length. This bar is pivoted at one edge, and the elevation of its free edge is maintained by a spring or counter-weight, m , as shown. This weight is so proportioned as to sustain the lever when idle, but to yield when the lever crowds downward, as it will when the tentative engagement is in action.

As the braking force which may be judiciously applied to an empty car is limited in comparison with what may be applied to a loaded car, and as the stress with which the draw-bar will be moved depends largely upon the momentum of other cars in the train, it follows that without provision for proportioning the intensity of brake application to the weight of the car I am unduly limited in the amount of braking force which I can utilize. Therefore I wish to effect an automatic proportioning of braking stress to the weight on the wheels. This I accomplish by the devices shown in Fig. 1, wherein the pulley b^2 , over which the brake-chain is carried, is supported by a bolt, n , the shank of which passes through the body-bolster of the car, and has a nut or head, o , over a spring, p , which is compressed when an appropriate stress is applied to the chain $b' b f$. This spring p , by its compression, affords relief to the apparatus in preventing undue stress in the application of the brakes, and will be adapted to permit the appropriate intensity of brake application when the car is empty, even though the draw-bar be fully acted upon. The spring-plank q has attached to it firmly at $q' q'$ a bridge, r , of iron plate, the top r' of which spans the truck-bolster s . By this arrangement any settling of the car from an increase of load will bring the body-bolster t nearer the bridge-plate r .

Attached to the body-bolster t is the fulerum u of a bell-crank v . One arm of this bell-crank rests against the follower-plate of the spring p . The other arm carries a lug or adjustable bob, u' , which is by the settling of the car-body brought into contact with the bridge r' . By these devices, when a car is loaded, the pressure on the lug u' causes the bell-crank to compress the spring p , by means of which said spring is prevented from acting through its resilience in so great a degree to relieve the stress upon the brake-beams transmitted by the chain $b' b f$. With this condition present the motion of the draw-bar will greatly increase the intensity of brake application. The tie-rod d' of the balanced brake-beams is caused, by means of common devices for converting longitudinal motion into rotary motion, to turn the adjustment-bar j , presenting its edges alternately to the top of the lug and the lever when the beams change position.

Figs. 1 and 3 show a device in which the required rotation of the engagement-bar j is communicated from the longitudinally-moving tie-rod d' by chains w , passing around idle-pulleys $z z$ on the frame, and coiled on pulleys $z' z'$, keyed to the gudgeons of the engagement-bar. The same effect is in some cases produced by a rack and pinion in combination

with beveled gearing. If preferred, the engagement-bar may be lifted away from its set position by a parallel movement imparted by a pitman, 25, jointed at 26 to the extremity of the lever 27, which is pivoted at 28 to the tie-rod *d* and fulcrumed at 29. With this device the pitman will have an endwise movement equal to the sine of the arc described by the end of the lever which carries it. The free end 10 of the pitman is jointed to the crossed centers of compound levers 30 31, of which the former is fulcrumed at 32 to the frame, and the latter at 33 to the engagement-bar *j*, their free ends working in slots in the engagement-bar and frame, respectively, so that a parallel motion will be imparted to the engagement-bar by the endwise movement of the pitman 25. (Shown in Fig. 7.)

The device for imparting a differential movement to the motor-lever from the longitudinally-moving draw-bar is shown in Fig. 4. It consists of a fixed plate, 2, provided with two oblique or cam slots, 3 3, which control the radial distance of the operating end of the pitman *y* relatively to the motor-lever by means of a guide-pin, 4, extending through the said cam-slots, and through a longitudinal slot, 5, in the motor-lever. The effect of this device is to throw the operating end of the pitman *y* 25 outward from the fulcrum-joint of the motor-lever as the draw-bar approaches the termination of its braking or reversed stroke, in whichever way the cars are moving, so that as the braking or reversed movement of the draw-bar progresses, it will actuate the motor-lever 30 with gradually-increasing force and corresponding decrease in extent of motion.

Any novel subject-matter that I have described and not claimed is reserved to be claimed 40 in future original applications.

Having thus described my invention, the following is what I claim as new therein and desire to secure by Letters Patent:

1. The combination, with a suitable brake-chain connection, of a vibrating lever transmitting stress from the draw-bar to the brakes, with a yielding supporting-bar set in a chord of the arc described by said lever, said bar being supported by a counter-weight or spring, 45 substantially as described.

2. In a draw-bar brake, the combination, with the draw-bar, of a motor-lever, *x*, actuated thereby through a pitman-connection, *y*⁴, changed automatically in radial distance from the lever-fulcrum, and causing a decrease in the extent of motion, and an increase in the amount of stress as the motion of the draw-bar progresses.

3. In combination with suitable brake-chain 55 connections, a lever transmitting stress from

the draw-bar to the brake-chains, and the vibrating bar *j*, having a guiding-face in a chord of the arc described by the end of the lever, and determining its adjustment in the plane of rotation of said lever, and consequently its engagement or disengagement with the devices through which it communicates stress to the brakes.

4. The combination of the draw-bar motor pitman *y*, cam-slots 3 3, guide-pin 4, and slotted motor-lever *x*, substantially as and for the purposes set forth.

5. The combination of the looped chain *f b* *b'*, pulleys *b²* *b³*, fulcrum-rod *n o*, and relief-spring *p*, substantially as and for the purposes set forth.

6. The combination of the brake-chain *f b b'*, follower-pulley *b²*, relief-spring *p*, and the bell-crank lever fulcrumed to the body of the car, forming at one end an abutment for the relief-spring, so as to graduate the strength thereof, and bearing at its other end against an attachment to the car-truck.

7. The lug or bob *u'*, longitudinally adjustable on the bell-crank lever *v*, in combination with the said bell-crank-lever *v*, and bridge *r* for regulating the value of motion received by the bell-crank for a determined movement of the car-body, substantially as and for the purposes set forth.

8. In combination with the supporting-lever and brake-chain connections, the chain-carrier *g*, moving on guide bars or rods for transmitting the stress of the draw-bar to the brakes.

9. The combination of the chain-carrier *g*, with its lug *h*, the motor-lever *x*, the bar *j*, and the looped chain *f b b'* for transmitting stress to the brake system by a movement of the draw-bar in either direction, according to the adjustment of the apparatus, substantially as explained.

10. The combination of the motor-lever and chain-carrier having oblique engagement-faces sloped in excess of the angle of friction to permit the escape of the lever from the chain-carrier when released, as explained.

11. The combination, with suitable brake-chain connection, of the motor-lever, chain-carrier, oblique lug, and chain-loop, substantially as and for the purposes set forth.

12. The combination, with suitable brake-chain connections with the motor-lever *x*, chain-carrier *g*, and its lugs *h* and *k*, of the adjustable engagement-bar *j*, substantially as and for the purposes set forth.

DOLPHUS TORREY.
